UNITED STATES PATENT OFFICE.

HENRY C. WARD, OF CHIPPEWA LAKE, MICHIGAN.

FOLDING UMBRELLA.

SPECIFICATION forming part of Letters Patent No. 480,482, dated August 9, 1892.

Application filed October 21, 1891. Serial No. 409,421. (No model.)

To all whom it may concern:

Be it known that I, HENRY C. WARD, a citizen of the United States, residing at Chippe-
wa Lake, in the county of Mecosta and State
5 of Michigan, have invented a new and useful
Folding Umbrella, of which the following is
a specification.

This invention relates to folding umbrellas;
and it has for its object to provide an um-
10 brella of this class which can be folded into
a small and compact form and can be easily
carried in a grip or placed in other receptacles
of small compass, and thus is capable of easy
transportation, while at the same time it pro-
15 vides a construction strong and durable and
which when the umbrella is opened provides
an article of equal strength with umbrellas
of the ordinary type which are not folded.

With these and other objects in view the
20 invention consists in the novel lock-hinge
and the arrangement and the applications
thereof to an umbrella, as will be hereinafter
more fully described, illustrated, and claimed.

In the accompanying drawings, Figure 1 is
25 a vertical sectional view of an umbrella con-
structed in accordance with my invention, the
same being opened. Fig. 2 is a similar view
showing the same folded. Fig. 3 is an en-
larged detail view of the rib-hinge in its
30 opened or locked position. Fig. 4 is a similar
view showing the same folded. Fig. 5 is a de-
tail in perspective of the rib-hinge, showing
the two members in position for assembling.
Fig. 6 is a detail view of the handle-coupling.

35 Referring to the accompanying drawings,
A represents the stick of my improved um-
brella and which is illustrated in the draw-
ings as comprising three distinct sections a a
 a , which are provided at their ends, which are
40 designed to be coupled together, with the fer-
rules a' . The notch and intermediate section
of the stick are provided with the projecting
screw-threaded bolts a^2 , bifurcated at their
45 ends, as at a^3 , and securely clamped to the
adjacent sections by means of the aforesaid
ferrules, while the ferrule a' of the handle-
section and that ferrule of the intermediate
section adjacent to the notch-section are pro-
50 vided with the interiorly-threaded hollow
portion h^4 , within which hollow portion the
headed bolt a^5 is designed to loosely work,
but is prevented from being withdrawn

through said threaded opening by means of
the flange or head a^6 , while its protruding end
is provided with a bifurcated portion a^7 , that 55
is engaged by the coupling-link B, that is
pivoted between said bifurcated end of said
bolt a^5 and the bifurcated end of the bolt
 a^2 . It can be readily seen that the bolt a^5
and the coupling-link B may be shoved 60
within the hollow threaded ferrule, while the
threaded bolt a^2 may be screwed therein,
thus securely coupling the several members
of the stick securely together and providing
a connection which, while providing a strong 65
stick, hides the parts which couple the sec-
tions together and which, when the bolt a^2 is
unscrewed from within the threaded ferrule,
provides a coupling which allows the inter-
mediate section to be folded up against the 70
notch-section, while the handle-section proper
folds downward, and thus allows the stick to
be folded within the umbrella-frame and in
a small compass.

Near the end of the notch-section of the 75
stick is secured the ordinary notched collar C,
to which are pivoted the inner ends of the
ribs D, over which the cover E of the um-
brella is stretched, and in the present in-
stance said ribs D comprise the folding-sec- 80
tions d and d' , respectively, which are coupled
together by means of the folding lock-hinges
F. Said lock-hinges couple the ends of the
rib-sections together and themselves com- 85
prise the opposing and jointed sections f and
 f' , respectively, the member f being illus-
trated in the drawings as receiving the end
of the rib-section d , while the other member
 f' is illustrated as being rigidly connected 90
with the end of the outer rib-section d' , that
is designed to be folded within the portion of
the cover stretched over the inner rib-sec-
tion d in a manner that will be apparent.
The member f' , which is connected to the 95
outer rib-sections d' , is provided with the
lugs f^2 , while the opposite member f , which
is connected to the inner rib-sections d , is
provided with the projecting tongue f^3 , pro-
vided with the longitudinally-disposed slot
 f^4 , formed in the face thereof, said tongue be- 100
ing designed to work between the lugs of the
opposite member and being jointed therein
by means of the pivot-bolt f^5 , passing through
said lugs and the slot in the tongue therein,

while said member *f* is further provided with the inwardly-projecting lug *f*⁶, to which are pivoted the braces *G*, pivoted also to the runner *H*, working on the notch-section of the stick 5 and adapted to open and close the ribs of the umbrella in the ordinary manner and working over and against the ordinary spring-catches *h*, with which umbrellas are usually provided. It can be readily seen now that the 10 folded umbrella may be opened by sliding the runner from its position adjacent to the notch until it is locked by the catch *h*, thus opening the inner rib-section and allowing the outer rib-section *d'*, folded up within the inner portion of 15 the umbrella, to be readily straightened out in view of the hinge-coupling *F* joining the same together, and that by pressing the outer rib-sections in a straight line with the inner sections the slot near the outer end of the 20 tongue in the inner of the members of said hinge will allow the pivot-pin *f*⁵ to slide within, which action will cause the tongue to be locked within the lugs of the outer member of the hinge, inasmuch as the joint cannot be broken 25 until the said hinge members are drawn away from each other sufficiently to allow the tongue of one to clear the top portion of the other, beneath which the said tongue is located. It can be readily seen now that the outer portion 30 of the umbrella-frame may be folded up within the inner portion, as may also be the sectional stick, and thus providing a folding umbrella which may be confined in an exceedingly small compass, while at the same time there 35 is provided a strong and rigidly-connected article fully answering all the requirements of an umbrella.

Having thus described my invention, what I claim, and desire to secure by Letters Patent, is—

1. In an umbrella, the combination, with a sectional stick, of the ribs made in two parts and hinged together by an inwardly-breaking lock-hinge and the radial braces fixedly pivoted to said hinges and to the sliding runner, 45 the outer portions of said ribs and the umbrella-cover being adapted to be folded under and within the inner portion, substantially as set forth.

2. In an umbrella, the combination of a sectional stick adapted to be folded up and within the umbrella-frame, the ribs made in two parts, inwardly-breaking lock-hinges coupling the rib-sections together and adapted to lock the same in their open position and to allow the 55 outer rib-sections to be folded only up and under the inner portion of the cover and the ribs, and the radial stretchers fixedly pivoted to the inner portions of said hinges and to the sliding runner, substantially as set forth. 60

3. In an umbrella, the combination, with a sectional stick, of the ribs made in two parts, inwardly-breaking lock-hinges joining the rib-sections together, said hinges comprising the opposite members, one member of which is 65 provided with parallel lugs and the other member with a projecting tongue having a slot near its outer end and adapted to work within the lugs of the opposite member and over a pivot bolt or pin passing through said lugs 70 and said slot, and the radial braces pivoted to the inner members of said hinges and to the sliding runner, substantially as set forth.

In testimony that I claim the foregoing as my own I have hereto affixed my signature in 75 the presence of two witnesses.

HENRY C. WARD.
